EXTENSIBLE CONNECTOR

Henry F. Ebert, Brooklyn, N. Y.

Application May 9, 1947, Serial No. 747,002

5 Claims. (Cl. 24—71)

1

This invention relates to an extensible device that is particularly useful for wrist watch straps, but is not restricted to such use as it is suitable for bracelets, bands and other devices where adjustments are needed because of different sizes of objects upon which this device is used.

The invention may be understood from the description in connection with the accompanying drawing in which:

Fig. 1 is a top view of an illustrative embodiment of the invention in closed position;

Fig. 2 is a section along the line 2—2 of Fig. 1, with parts in normal relative positions when the device is in use;

Fig. 3 is a section along the line 3—3 of Fig. 2;

Fig. 4 is a bottom view of Fig. 2;

Fig. 5 is a section along the line 5—5 of Fig. 2;

Fig. 6 is a plan view of parts below the line 6—6 of Fig. 2;

Fig. 7 is a longitudinal section similar to Fig. 2 with parts in positions slightly different from those of Fig. 2;

Fig. 8 is a section along the line 8—8 of Fig. 7;

Fig. 9 is a sectional view similar to Fig. 7 with parts in other positions;

Fig. 10 is a perspective view of one of the parts shown in Fig. 9;

Fig. 11 is a plan view of a modification; and

Fig. 12 is a transverse section along the line a—a of Fig. 11 on an enlarged scale.

In the drawings, reference character 1 indicates a top curved link having side walls 2, 2' and an integral ring 3 at one end thereof. The other ends of these side walls are provided with holes 4 in which the lugs 4' of a link 5 of resilient material are pivoted. This link 5 is provided with a curved extension 5' along the top side thereof a short distance from lugs 4'. Longitudinal strengthening edges 6 are provided on the link 5. The other end of this link is flattened, as shown at 5'', and integral pivot lugs 7 on the edges of this link 5 extend into holes or bearings in the side walls or flanges 8 of a link 9 that is curved like link 1, and is narrow enough to be nested between the side walls 2 and 2' of link 1. The other end of link 9 is provided with an inwardly projecting stop 9' and side flanges 10, one of which has a notch 11 therein. A curved slidable locking member 12 having a ring 13 at one end for a cross pin, and flanges 14 along its edges, is slidably mounted in link 9. The upper edges 8' of the flanges 8 of link 9 are turned inwardly and guide slidable locking member 12 in link 9. An integral projection 15 is provided on slidable member 12 to limit the outward movement of

slidable locking member 12 as it strikes the stop 9' at the end of link 9. Teeth 16 are provided along a flange 14 of the slidable locking member 12, and a catch 17 having a sloping edge is provided along the edge of flange 2'.

In the modification shown in Figs. 11 and 12, the link 20 with side walls 20' corresponds to the link 1 and walls 2 of other figures. The link 22 of springy material corresponds to link 5, the flanges 23 to flanges 2, the link 27 to link 9. In this modification there is a slot 31 in each flange 29 corresponding to the slot 11 of other figures. Slidable locking member 31 corresponds to locking member 12, and slots 31 correspond to slot 11. The main difference in this modification is that a catch or tooth 36 corresponding to catch 17 is provided on each side of the device and each flange 20' on link 27 is provided with a slot 31.

The operation will be described in connection with its use as a wrist watch strap, although the device is not limited to this use.

The ends of a wrist watch strap are connected to the rings 3 and 13 and the device is slipped over the hand with the top piece 1, link 5 and bottom piece 9 unfolded and with the slidable locking member 12 in an extended position. The parts 1, 5 and 9 are then folded and the slidable locking member 12 is adjusted inwardly in accordance with the size of the wrist.

As each tooth 16 along the edge of the flange 14 of the slidable locking member 12 reaches the catch 17 and passes by, it snaps behind this lug with the straightened edge of the tooth behind the large inner end of this catch 17, which is at right angles to the movement of the teeth, thus keeping the parts in adjusted positions.

When it is desired to open or expand the device for removal of a wrist watch from the wrist, pressure with the thumb is applied to the lower side of link member 9, thus moving the lugs 7 and right hand end of flexible link 6 upwardly and raising the catch 16 on the flange 14 out of contact with the tooth 17 on one of the flanges 2' of the slidable locking member 12 as shown in Fig. 7, whereupon this sliding locking member 12 can be drawn out until the projection 15 strikes the stop 9' on link 9. As soon as the end of catch 12 passes beyond the catch 17 the three members 1, 5 and 9 can be opened so that the rings 3 and 13 are nearly four times as far apart as they are in their closed or nested position.

When it is desired to return the parts to the closed locked position of the device, one merely folds the parts 1, 5 and 9, presses them together between thumb and forefinger and pushes the slid-

able member 12 inwardly until a tooth 16 on it is brought to a position where it will catch behind the opposite or far edge of catch 17 on flange 2'. The spring pressure due to the extension 5' on link 5 urges the right hand end of link 9 downwardly so that as soon as pressure of the user's finger on this link is removed the right hand end of the locking member 12 moves downwardly, causing a tooth 16 to catch behind the catch 17 with this lug under catch 12 so that it cannot be pulled out.

The slideable locking member 12 is adjusted inwardly after the links have been folded together merely by pushing it until the desired tooth 16 has reached the catch 17.

The operation of the modification shown in Figs. 11 and 12 is like that described above, but there is a lug 36 on each flange 20' to catch in teeth.

What is claimed is:

1. An extensible connector comprising two flanged links connected by a resilient link having its ends pivoted in the flanges of said links, and having a projecting portion near a pivoted end thereof adapted to press against one of said flanged links when the parts are in folded position, a toothed member slideable in one of said flanged links and a lug on the flange of the other of said links adapted to engage the teeth of said toothed member and maintain them in adjusted positions.
2. An extensible connector comprising three curved foldable pivoted members, a resilient middle member having a projection near one end thereof adapted to press against the adjacent member when said members are in folded position, a slideable member in one of said end members

5 members having a toothed flange, the other end member having flanges along its edges with an inwardly extending lug at the edge of one of said flanges, the first end member having flanges, one of which is provided with a slot for said lug.

3. An extensible connector comprising three pivoted links, the first and third ones having side walls in which the second one is pivoted at opposite ends thereof, the first one having an inwardly extending lug on the outer edge of one of its side walls, the second one having an extension on its top side near where it is pivoted to the first link, the third one having inwardly extending flanges along the edges of its side walls and a notch for said lug in one of its side walls and corresponding flange, and a slide in the third one of said links carrying teeth to engage said lug and hold said links in folded position.

4. The connector of claim 3 in which said second link is springy and the others are rigid.

5. The connector of claim 3 in which said teeth have one side sloping and the other side perpendicular to the slide which carries them when said links are in folded position.

HENRY F. EBERT.
